MOTION PICTURE PROJECTOR

Robert Mees, Wissmar, Kreis Wetzlar, and Heinrich Janke, Wetzlar (Lahn), Germany, assignors to Ernst Leitz Gesellschaft mit beschränkter Haftung, Wetzlar (Lahn), Germany

Filed Sept. 26, 1961, Ser. No. 66,861

Term of patent 14 years

(Cl. D61—1)

Fig. 1

Fig. 3

Fig. 2

Fig. 5

Fig. 4

FIGURE 1 is a side perspective view of a motion picture projector showing our new design, the reel support being shown in the closed position;

FIGURE 2 is a front elevational view thereof;

FIGURE 3 is a rear perspective view thereof;

FIGURE 4 is a side perspective view similar to that of FIGURE 1, the reel support being shown in the open position;

FIGURE 5 is an overall perspective view of the projector as shown in FIGURE 1.

The broken-line showing of the reels in FIGURE 4 is for illustrative purposes only.

We claim:

The ornamental design for a motion picture projector, as shown and described.
